UNITED STATES PATENT OFFICE.

JOSEPH A. GENDRON, OF NASHUA, NEW HAMPSHIRE.

WEFT-REPLENISHING MEANS FOR LOOMS.

SPECIFICATION forming part of Letters Patent No. 767,934, dated August 16, 1904.

Application filed June 11, 1901. Serial No. 64,084. (No model.)

To all whom it may concern:

Be it known that I, JOSEPH A. GENDRON, a citizen of the United States, and a resident of Nashua, county of Hillsboro, State of New Hampshire, have invented certain new and useful Improvements in Weft-Replenishing Means for Looms, of which the following is a full, clear, and exact description.

The object of my invention is to produce a loom having features of novelty and advantage over those now in use.

Referring to the drawings, Figure 1 is a front elevation of a loom in which my invention is embodied. Fig. 2 is an end view of the same. Fig. 2^a is a detail view of the tripping and returning mechanism, on enlarged scale. Fig. 2^b is a detailed plan view of catch-plate *a*¹⁵. Fig. 3 is a top view on the line *xx* of Fig. 1. Fig. 3^a is a detail view of the tripping device, on enlarged scale.

Referring to the drawings, *A* denotes the frame of a loom, and *B* denotes the lay-frame, which is pivoted in the loom-frame and is of the ordinary construction adapted to swing in one direction while the warp-threads are separated or shed to permit a passage of the shuttle and in the opposite direction to lay the weft-thread in each passage of the shuttle through the warp. The power-shaft *C*, which drives the moving parts of the loom, is mounted on the loom-frame, as at *D*, and is connected by links with the lay-frame, as shown clearly in Figs. 2 and 3, so that as the shaft revolves it will impart an oscillating movement to the lay-frame, this connection being arranged to move the lay-frame to beat up the thread which has been passed through the warp by the shuttle on the top of the lay-frame. At each end I mount what may be called "shuttle-carriers" *E F*, which control the movement of the shuttle to and fro through the warp-threads. These carriers have a limited movement toward and away from each other, which movement is controlled by the levers *G*, pivoted at their lower ends to the lay rock-shaft and having lugs *H* projecting therefrom, which work in cam-slots *a* in stationary plates *I*, which are secured to the loom-frame. Figs. 1, 2, and 3 show this cam-slotted plate and the lugs on the levers *G* and

the connecting of these levers with the shuttle-carriers. It is clear that as the lay-frame oscillates under the impulse of the power-shaft the lugs on the levers *G* will travel in the cam-slots, moving the shuttle-carriers *E F* toward each other at the same time. These carriers are provided with spring gripping-fingers. In their movement toward each other they come so near together as to permit the empty carrier to grip the end of the shuttle and remove it from the jaws of the other carrier, whose grip on the shuttle has been automatically released. This feature of the invention constitutes the subject-matter of a divisional application filed by me on August 17, 1901, Serial No. 72,406, which became Patent No. 714,169, dated November 25, 1902.

In connection with this loom and shuttle-carrier I have provided a means for supplying to the carrier a full shuttle as soon as the thread in the one in use is spent. This system comprises the use of a rack *d*, arranged to slide vertically in the frame *e* and normally held in its raised position by the springs *f*. From the rear of this rack projects a lug *g*, and pivoted in the frame which supports the rack are the fingers *h i*, preferably pivoted on the same rock-shaft, the fingers *h* engaging the lug on the rack to move it downward when the finger is moved, and the fingers *i* are arranged to strike a shuttle at each end when the rack is in its lower position and knock the empty shuttle from the carrier and put in its place a full shuttle. The movement of these fingers is controlled, primarily, by a suitable stop-motion device, which, with its connections, is illustrated in Fig. 2. A slide *a*¹⁰ carries at one side a weft-fork *a*¹¹ and at its opposite side is connected through the arm *a*¹³ with the shaft *a*¹², carrying the cam *a*¹⁴, which operates against a lever *b*. The upper end of this lever *b* projects through a slot *a*¹⁷ in the plate *a*¹⁵, this slot being provided with the shoulder *a*¹⁶. The lever *b* is also connected with one end of a rock-shaft *c*. At its opposite end this rock-shaft is connected with a finger *m*, as by the link *n* and the crank-arm *o*, the finger *m* being pivoted to one end of a pivoted lever *l*, which at its opposite end is connected with the lever *k* by a link *j*. On the power-shaft is a gear *M*,

meshing with the gear N, mounted on the jack-shaft K, the gear N being preferably twice the size of the gear M. Secured to the power-shaft adjacent to the gear M is a sleeve 5 L, having pivoted to it a trip device having arms p r. A lug s on the gear M is arranged to strike the arm r of the trip device at every revolution, which will be at every second revolution of the power-shaft. The relative 10 position of the parts when the machine is running is shown in plan view in Fig. 3, the finger m being thrown to one side to the path of movement of the arm p.

If the thread happens to break or become 15 spent, the weft-fork a¹¹ on the slide a¹⁰, acting in the usual manner through the arm a¹³, rocks the shaft a¹² and causes the cam a¹⁴ to disengage the lever b from the shoulder a¹⁶ in the slot a¹⁷, formed in the plate a¹⁵. Upon being 20 released from the shoulder a¹⁶ the lever b is thrown forward, rocking the shaft c and bringing the arm o and the finger m into the position shown in dotted lines in Fig. 2^a. When the lug on the gear strikes the arm r, it will 25 throw the arm p to the position shown in dotted lines in Fig. 3^a and in full lines in Fig. 2^a directly over the finger m. The arm p, revolving with the shaft, will press down the finger m and rock the lever k on its pivot l, 30 throwing the link j upward and rocking down the fingers h i i. The finger h carries with it the rack holding the shuttles, and when it is in its lowest position the fingers i engage each end of the shuttle and force it down between 35 the gripping-fingers of the shuttle-carrier, pushing the empty shuttle into a box or some such receptacle in the lower part of the loom. As the finger m is pressed down by the arm p it rides down the inclined face of 40 the face t, which throws it to the left and through the link n and the crank-arm o rocks the shaft c back to its normal position, engaging the lever b with the shoulder a¹⁶ in the plate a¹⁵. The ends of the threads from each of the 45 shuttles as they are in the rack are passed through a notch in the post v, as shown in Fig. 2, so that as a new shuttle is delivered to the carrier this thread will be held during the initial movement of the shuttle across the 50 warp.

I claim as my improvement—

1. In a loom in combination the shuttle-carrier, the shuttle-rack movable vertically, and means for automatically delivering the 55 full shuttles from said rack to said carrier.

2. In a loom in combination the shuttle-carrier, a stop-motion device, the shuttle-rack movable vertically, and means controlled by a stop-motion device for automatically delivering a full shuttle from the rack to the carrier, 60 substantially as described.

3. In a loom, in combination, the shuttle-carrier, the rack movable in a vertical plane and arranged in operative relation to said carrier and adapted to receive and retain shuttles, means for moving the shuttle from the rack to the carrier, a stop-motion device, and automatically-operated connections between said means and the stop-motion device, substantially as described. 70

4. In a loom, in combination, the shuttle-carrier and its operating mechanism, a stop-motion device, a rack, adapted to receive and retain shuttles, mounted in operative relation to said carrier, and automatically-operated 75 means for moving the shuttle from the rack to the carrier comprising a system of levers having a pivoted arm adapted to move in a horizontal plane, connections between this pivoted arm and a stop-motion device, and a 80 revolubly-mounted trip, arranged to engage said pivoted arm when it is moved from its normal position by the action of the stop-motion device, substantially as and for the purposes specified. 85

5. In a loom, the combination with the shuttle-carrier, the rack arranged to receive and retain the shuttles, said rack being held normally in its raised position by springs, and automatically-operated means for moving said 90 rack downwardly, and means for moving a shuttle from the rack to the carrier, substantially as described.

6. In a loom, the combination with the shuttle-carrier, the shuttle-holding rack and a 95 stop-motion device, of means interposed between said rack and the stop-motion device for operating the rack, said means comprising a horizontally-pivoted arm and a coacting revoluble trip, said arm being normally held out of the path of movement of said trip, automatic means for throwing said arm into the path of movement of said trip, and means for returning said arm to its normal position, substantially as described. 100
